BAKING OVEN

Louis D. Houlis, Dallas, Tex.

Application April 10, 1934, Serial No. 719,833

5 Claims. (Cl. 107—59)

This invention relates to new and useful improvements in baking ovens.

One object of the invention is to provide an improved oven wall construction, whereby the 5 heat is evenly distributed within the oven, but is kept from excessively radiating through the wall and dissipating over the outer surface.

Another object of the invention is to provide an improved heating and ventilating system and 10 so arranged that when the temperature drops below a predetermined degree a maximum amount of fuel is supplied to the burners and at the same time ventilation is automatically controlled. Also whereby when the desired temperature is reached, both the fuel supply and the 15 ventilation are automatically cut to a minimum point.

A further object of the invention is to provide an improved oven door co-acting with the 20 ventilating means for operating the latter when the door is opened and closed, whereby excess heat is conducted to the flue instead of flowing into the baking room and also whereby heat is conserved when said door is opened.

25 Still another object of the invention is to provide means whereby the heat and ventilation are proportionately controlled and cold air currents are prevented from circulating in the baking chamber and waste heat is also obviated.

30 A construction designed to carry out the invention will be hereinafter described, together with other features of the invention.

The invention will be more readily understood 35 from a reading of the following specification and by reference to the accompanying drawings, in which an example of the invention is shown, and wherein:

Figure 1 is a perspective view of an oven constructed in accordance with the invention,

Figure 2 is a horizontal cross-sectional view of the oven, portions of the oven floor being omitted to show underlying pipes,

Figure 3 is a transverse vertical sectional view 45 of the oven,

Figure 4 is a detail of the corner construction, Figure 5 is a sectional detail of the wall,

Figures 6 and 7 are details of the operating connections for the front damper,

50 Figure 8 is a horizontal cross-sectional view of the door structure,

Figure 9 is a vertical sectional view taken on the line 9—9 of Figure 8,

Figure 10 is a partial elevation of the door mechanism, and

Figure 11 is a detached view of the thermostatically controlled fuel valve.

In the drawings the numeral 10 designates the front wall, 11 the back wall, 12 the end walls, 55 13 the top or roof, and 14 the floor of the oven.

The oven is given a general rectangular shape which lends to the structural details thereof. Each wall 10, 11, 12 and 13 is substantially the same and a description of one will explain all.

In building the wall an inner frame 15 and an 5 outer frame 16 are constructed. These frames are formed of angle bars and are rectangular in shape. Each frame is provided with uprights 17, preferably made of angle bars. The frames are spaced apart with their flanges directed inwardly 10 so that the flat sides of the bars face outwardly. Connector straps 18 extend between the frames at intervals and constitute the only connections therebetween. It is preferable to weld frame bars, uprights and straps in place, thus avoiding 15 rivets or bolts and making a more substantial construction.

Each wall has an outer covering or shell formed of one or more metal sheets 19 welded or otherwise secured to the outer flat faces of the frame 16 and uprights; while one or more sheets 20 are welded or otherwise fastened to the outer flat faces of the frame 15 and uprights, to form 20 the lining of the oven. The inner sheets 20 may be made of any desirable sheet metal, such as 25 copper alloy steel; while the outer sheets 19 may be of heavier rust resisting metal. Suitable insulating material, such as mineral wool 21, is packed in the walls between the shell and the lining and this has been omitted from the drawings, except at portions in order to better illustrate the structure. Retainer strips 22 are placed 30 in the frames at their bottoms to support and retain the insulating material.

35 In setting up the oven the inner frames 15 are bolted together, as is shown at 23 in Figures 2 and 5, along the upright corners. In order to seal the baking chamber the inner sheets 20 of one wall may be bent around the frame so as to lie flat against the marginal portions of the lining of the other frame, as is shown in Figure 5. The top frame 15 is bolted to the other frames 15 by bolts 24. To complete the corners, angular battens 25 are secured to the outer frames 16, as is shown in Figures 4 and 5, by bolts 26. These 40 battens not only provide rounded corners but tie the frames together. Similar battens 27 are bolted to the tops of the frames 16 and the frame 16 of the top 13, by bolts 28, as is shown in Figures 1, 3 and 4. The corners and connections thus formed are also filled with insulating material.

45 The chamber formed by the walls which have been described is supported in a base which is formed by sills 29 disposed under the end walls 12 connected by angle bars 30 extending under the front and back walls. The battens 25 may be extended down to cover the corners of the base. The floor 14 is supported on a pair of angle bars 31 extending between the sills at the center 50 55 60

of the floor and longitudinally of the oven. The floor is inclined downwardly from the bars 31 and bent under the bars 30, as is shown in Figure 3. As before stated, welding is employed where it is desired to fasten parts together.

At mid-height an elongated door flange 32 is provided longitudinally of the front wall 10 and a shelf 33 extends outwardly from the bottom of this frame. The upright ends of the frame are 10 provided with slots 34. A sliding door 35 has upright T-shaped rails 36 engaging in the slots, as is shown in Figures 8 and 10. The door 35 is considerably narrower than the front wall 10 (Figures 3, 8 and 9) and has its inner surface 15 substantially flush with the lining 28. The lining has a pocket or recess 37 for receiving the door 35 when the latter is slid downwardly to open it.

The rails 36 depend from the door and chains 38 are fastened thereto. These chains pass over 20 sprockets 39 and carry counterbalancing weights 40, whereby the door is held in the position to which it is moved, open or closed. The sprockets 39 are fastened on a shaft 41 extending through the end walls 12. Hand wheels 42 are fastened 25 on the ends of the shaft, whereby the shaft may be rotated from either end of the oven to open or close the door.

A revolving reel 43 is journaled in the oven. A flat flue or manifold 44 is formed longitudinally 30 in the central portion of the top 13. The manifold has a vent 45. A rear arch sheet 46 curves downwardly from the rear portion of the manifold to the top of the upright flue 41 mounted on the rear wall. This flue terminates short 35 of the bottom 14 and its purpose is to carry off excess heat. A front arch sheet 48 curves downwardly from the front portion of the manifold 44 toward the front wall 10 and has its lower end spaced from the lining 28 by a bracket 49 just above the door frame 32. These arch sheets 40 obviate corner pockets in the top of the baking chamber and properly deflect the heat currents onto the reel. Above the rear arch 46 a damper 50 is hinged in the bottom of the manifold so that 45 air currents passing up the flue 47 may be discharged into the manifold when the damper is opened. This damper is mounted on a shaft 51 and is hinged in the end walls 12.

A similar front damper 52 is mounted in the 50 bottom of the manifold overhanging the arch sheet 48. When this damper is opened air currents and fumes passing through the bracket 49 will be conducted to the manifold. This damper is mounted on a shaft 53 journaled in the end 55 walls 12. This provides for ventilation when the door is opened so as to carry off the fumes and hot air currents instead of permitting them to flow into the room.

In the bottom of the oven I provide burners 60 disposed longitudinally of the central portion thereof. These burners may be of any suitable structure and are employed for producing a maximum heat. A longitudinal burner 55 is disposed between the burners 54 and is of the 65 finely perforated type for producing minimum heat. Fuel pipes 56 mounted under the floor 14 extend inwardly from the front of the oven and are connected with the burners 54 through said floor. These pipes have the usual mixing heads 70 57 on their front ends. The burners 54 are arranged in pairs and the heads of each pair are connected by a cross pipe 58. A manifold pipe 59 is mounted longitudinally below the pipes 56 and is connected at its ends with laterals 60, which 75 in turn are connected with the pipes 58. On each

side of the lateral connection hand valves 61 are connected in the pipes 59, whereby the supply of gas to each mixing head 57 may be controlled.

A fuel pipe 62 extends under the floor 14 and 5 is connected through the same with the burner 55. This pipe has a mixing head 63 on its front end similar to the heads 57. A branch pipe 64 extending from the head 63 is connected to a manifold pipe 65, which is attached at one end 10 to a cross connection 66 in the manifold 59 as is shown in Figure 2. A gas supply pipe 67 extending under the floor 14 is attached to the connection 66 and leads through one of the sills 30, as is shown in Figure 1. A smaller gas supply 15 pipe 68 leads through said sill and is connected in the pipe 65, as is shown in Figures 1 and 2.

The pipe 65 has a hand valve 69 for controlling the supply of gas coming thru pipe 68 to the connection 66 and a hand valve 70 beyond the 20 connection with the pipe 64. A flexible hose 71 is connected to the pipe 65 and carries a long nozzle 72. A swinging door 73 is mounted at the center and bottom of the front wall 10. By swinging this door outwardly, the nozzle may be 25 inserted into the baking chamber to light the burners. When the nozzle is not in use the valve 70 is closed. It is obvious that by operating the hand valves the supply of gas to the burners may be controlled.

A fuel supply pipe 74 is connected with the pipe 67, as is shown in Figure 1. An electrically operated valve 75, of the type now commonly in use, is connected in the pipe 74 and the minimum gas pipe 68 is connected in the pipe 74 ahead of said valve so that gas is constantly supplied to said pipe 68. The valve 75 has electrical connection with a thermostat 76 mounted in the adjacent end wall. These parts are of the usual construction, whereby the valve 75 is thermostatically controlled so as to open when a predetermined low temperature is reached in the oven and to close when a predetermined high temperature is attained. From the foregoing it will be seen that the burner 55 is constantly supplied 45 with gas so as to burn and provide a minimum heat. This burner serves as a pilot for lighting the burners 54 whenever they have been extinguished.

On one end of the shaft 41 which operates the 50 door 35 is journaled a collar 77, as is shown in Figures 6 and 7. This collar has an arcuate slot 78 receiving a pin 79 fastened in the shaft. An arm 80 extends from the collar when the shaft is rotated in a counter-clockwise direction (Figures 1, 6 and 7) and the pin will travel in the slot while the door 35 is being lowered. Just prior to the end of the shaft rotation the pin engages the end of the slot and rotates the collar, whereby the arm 80 is swung upwardly. This arm is connected by means of a link 81 with an arm 82 fastened on the end of the shaft 53 of the front damper 52. When the door is closed the damper 52 is closed. Therefore, when the door reaches its full open position, the damper 52 is opened by the mechanism which has been described. This provides ventilation so that the excess heat and fumes are carried out back of the arch 48 into the manifold 44, as before referred to.

For operating the rear damper 50, a lever 83 is fastened on the projecting end of the shaft 51. This lever is connected by a link 84 with an arm 85 extending from the valve 75. When the valve 75 is closed, the arm 85 is moved downwardly, 75

whereby the lever 83 is swung to close the damper 50; but when the valve is open the arm 85 is moved upwardly and the damper is thus swung open to set up ventilation in the baking oven.

From the foregoing it will be seen that a most efficient heating system is provided. Cold air currents cannot enter the baking oven except when the door 35 is open or by back-flowing from the manifold 44, which is hardly possible. After the burners have been set by adjusting the hand valves 61 and 69, the operation of the burners is entirely automatic. When the temperature drops to a predetermined degree, the thermostat 76 causes the operation of the valve 75, and immediately a maximum of gas is supplied to the burners 54, thru the pipe 67. At the same time the damper 50 is opened and ventilation is established by way of the flue 47 and arch 46 to the manifold 44. This not only provides the necessary heat, but properly ventilates the oven so as to carry off excess heat. The flue 47 having its entrance at the bottom of the oven prevents cold air entering the oven and also has a tendency to pull the excess heat from the top of the oven downwardly without producing a chilling effect. Just as soon as the maximum heat is reached the thermostat closes the valve 75, whereby the gas burners 54 are extinguished and the damper 50 is closed. The supply is reduced to a minimum being supplied by the pipe 68 and the burners remain lighted and serve to maintain the desired even heat in the oven.

It is pointed out that when the oven is first put into use, the hand valve 69 is opened. The gas from the main supply line 74 by-passes the electric valve 75 and flows thru the pipe 68, past the valve 69 and into the manifold 59. From the manifold, the gas enters any of the burners 54 which may have their individual hand valves 61 open. It is here brought out that the valves 61 are either wide open or entirely closed, the flow of gas thereto being controlled by the valve 69. The pilot burner 55 is supplied by gas from the pipe 65 as has been described, and has been previously lighted normally by the nozzle 72.

Thus whenever the valve 69 is opened, the burners 54 are supplied with gas and are ignited by the pilot 55. The valve 69 is open only sufficiently far to supply a minimum amount of gas to the burners 54. When the temperature of the oven falls to the predetermined low point, the thermostat 76 operates the electric valve 75 to permit gas to enter the manifold 59 thru the pipe 67 and supply the burners 54 with a maximum amount of gas. Whenever the valve 75 closes, the burners 54 are not extinguished but burn on a minimum amount of gas. With this arrangement, the burners 54 either burn at a maximum or a minimum, there being no intermediate position. However, if desired, the hand valves 61 can be individually adjusted to intermediate positions altho it has been found that by controlling the supply of gas by the valve 69, better results are obtained. It is noted that the pilot 55 is not connected with the manifold 59, being always manually controlled, while the burners 54 have the minimum gas supplied thereto manually controlled by the hand valve 69 and the maximum gas supplied thereto automatically controlled by the electric valve 75.

What I claim and desire to secure by Letters Patent is:

1. A baking oven including, walls each formed

of inner and outer frames, each frame comprising a plurality of angular members, a sheet secured to each outer frame, a lining secured to each inner frame, means for securing the inner frames together, angular battens connecting the outer frames, and narrow transverse straps spaced from each other extending between the inner and outer frames whereby said frames are secured together, the space between the frames being filled with insulating material. 5

2. A baking oven including, walls each formed of inner frames comprising a plurality of angle bars and outer frames also comprising a plurality of angle bars, said bars having their flat sides outward, a sheet secured to each outer frame, a lining fastened to each inner frame, the angle bars of the inner frames being bolted together, angular battens bolted to the outer frames, and narrow transverse straps spaced a considerable distance from each other extending 15 between the inner and outer frames whereby said frames are secured together, the space between the frames being filled with insulating material. 20

3. A baking oven including, a baking chamber 25 having a front ventilating arch and a rear ventilating arch, a burner for providing a minimum heat within the oven, a fuel supply line connected to said burner, a second burner for providing a maximum heat within the oven, a fuel supply 30 line, connected with said second burner, a single automatic control valve connected in the supply line, a door at the front of the oven adjacent the front arch, a damper controlling the ventilation of the front arch actuated by the door, and a 35 damper controlling the ventilation of the rear arch connected with the fuel control valve and actuated thereby.

4. A baking oven including, insulated walls, 40 burners in the bottom of the oven for supplying a maximum heat, a fuel supply line connected with said burners, a thermostatically controlled valve connected in said line for controlling the fuel to said burners, a minimum heat burner contiguous to the maximum burners, a fuel supply line having one end connected with the minimum heat burner and its other end connected to the first named supply line at a point beyond the thermostatic valve, whereby said minimum heat burner is constantly supplied with fuel, an oven ventilator in the upper end thereof, and means for connecting said thermostatic valve with said ventilator, whereby the ventilation of the oven and the fuel supply to the maximum heat burners is simultaneously accomplished. 45

5. A baking oven comprising, insulated walls, 50 burners in the bottom of the oven for supplying maximum heat, a fuel pipe connected with said burners, a minimum heat burner adjacent the maximum heat burners, a thermostatically controlled valve in the supply line for controlling the fuel supply to the maximum heat burners, means for by-passing a restricted amount of fuel around said valve to both the minimum burner and maximum burners to supply a reduced amount of 55 fuel to the maximum burners and to constantly supply said minimum burner, an oven ventilator directly connected to and actuated by said valve, whereby the ventilation is controlled in proportion to the fuel supplied to maximum heat burners. 60

LOUIS D. HOULIS. 70
